UNITED STATES PATENT OFFICE.

GEORGE H. ELMER, OF BALTIMORE, MARYLAND.

DESIGN FOR AN ADVERTISING-BREASTPIN.

SPECIFICATION forming part of Design No. 23,109, dated March 13, 1894.

Application filed November 9, 1893. Serial No. 490,482. Term of patent 3½ years.

To all whom it may concern:

Be it known that I, GEORGE H. ELMER, a citizen of the United States, residing at Baltimore, in the State of Maryland, have invented 5 and produced a new and original Design for an Advertising-Breastpin, of which the following is a specification.

Figure 1 is a perspective rear view of the breastpin, and Fig. 2 is a front view.

10 The head of the breastpin comprises a rectangular block, A, having a smooth flat front, b, provided with two concentric circle lines, and at the reverse side a smooth flat back, c, from which the pin projects, and at two op-

posite sides has diagonal lines, d, imitative 15 of or representative of the folded edges of a coating or sheathing over the head. The other two sides are flat and smooth.

I claim—

The design for an advertising breastpin, as 20 herein shown and described.

In testimony whereof I affix my signature in the presence of two witnesses.

GEORGE H. ELMER.
